CALUTRON

Martin D. Kamen, Berkeley, Calif., assignor to the United States of America as represented by the United States Atomic Energy Commission

Application October 31, 1944, Serial No. 561,272

9 Claims. (Cl. 250—41.9)

The present invention relates to ion source units, and more particularly to calutrons incorporating such units.

At the outset, it is noted that a "calutron" is a machine of the character of that disclosed in the copending application of Ernest O. Lawrence, Serial No. 557,784, filed October 9, 1944, now Patent No. 2,709,222, granted May 24, 1955, and is employed to separate the constituent isotopes of an element and, more particularly, to increase the proportion of a selected isotope in an element containing a plurality of isotopes in order to produce the element enriched with the selected isotope. For example, the machine is especially useful in producing uranium enriched with U²³⁵.

Such a calutron essentially comprises means for vaporizing a quantity of material containing an element that is to be enriched with a selected one of its several isotopes; means for subjecting the vapor to ionization, whereby at least a portion of the vapor is ionized causing ions of the several isotopes of the element to be produced; electrical means for segregating the ions from the un-ionized vapor and for accelerating the segregated ions to relatively high velocities; electromagnetic means for deflecting the ions along curved paths, the radii of curvature of the paths of the ions being proportional to the square roots of the masses of the ions, whereby the ions are concentrated in accordance with their masses and means for de-ionizing and collecting the ions of the selected isotope thus concentrated, thereby to produce a deposit of the element enriched with the selected isotope.

More particularly, a calutron of the type noted ordinarily comprises an evacuated tank housing a removable ion source unit including structure providing a charge reservoir and a communicating charge ionizing chamber. In the operation of such a calutron, ordinarily the charge reservoir of the ion source unit contains a charge of a suitable uranium compound capable of being vaporized, such for example as uranium tetrachloride or uranium hexachloride; and after a given charge in the charge reservoir is vaporized, operation of the calutron is arrested and air is admitted into the tank. Then the ion source unit is removed from the tank and another charge is placed in the charge reservoir; and thereafter, the ion source unit is replaced in the tank and the tank is sealed and again evacuated. At this time, further operation of the calutron is resumed in order to vaporize the new charge contained in the charge reservoir.

While the operation of a calutron in the manner described is generally satisfactory, the operating conditions are not ideal in certain respects in that it is necessary to remove the ion source unit from the tank each time another charge is placed in the charge reservoir; and of course it is necessary to admit air into the tank in order to increase the pressure therein each time the ion source unit is removed therefrom. Accordingly, the vacuum pumping apparatus associated with the tank must possess a larger gas handling capacity than is desirable.

Accordingly, it is an object of the present invention

2

to provide a calutron comprising an evacuated tank carrying an improved ion source unit having a charge reservoir that may be filled repeatedly with a suitable charge without appreciably increasing the pressure within the tank incident thereto.

Another object of the invention is to provide in a calutron comprising a tank having a removable wall, an improved ion source unit that is supported by the removable wall and includes structure defining a charge ionizing chamber disposed within the tank and a communicating charge reservoir disposed exteriorly of the tank, whereby the charge reservoir is readily accessible from the exterior of the tank.

Another object of the invention is to provide in a calutron comprising a tank supporting an ion source unit including structure defining a charge ionizing chamber disposed within the tank and a communicating charge reservoir, an improved arrangement controllable from the exterior of the tank for regulating the flow of charge from the charge reservoir to the charge ionizing chamber.

A further object of the invention is to provide in an ion source unit comprising structure defining a charge ionizing chamber and a communicating charge reservoir, improved valve mechanism for regulating the flow of charge from the charge reservoir to the charge ionizing chamber.

A further object of the invention is to provide in an ion source unit comprising structure defining a charge ionizing chamber and a communicating reservoir housing a normally closed receptacle containing a charge, mechanism for opening the receptacle and then for regulating the flow of charge therefrom into the reservoir and consequently into the charge ionizing chamber.

A still further object of the invention is to provide in an ion source unit including a receptacle containing a charge capable of being vaporized, an improved arrangement for heating the receptacle, whereby the rate of vaporization of the charge contained therein may be controlled.

The invention both as to its organization and method of operation, together with further objects and advantages thereof, will best be understood by reference to the following specification taken in connection with the accompanying

drawings, in which Figure 1 is a diagrammatic plan view of a calutron including an ion source unit embodying the present invention; Fig. 2 is a diagrammatic sectional view of the calutron taken along the line 2—2 in Fig. 1; Fig. 3 is a fragmentary longitudinal sectional view of the calutron ion source unit, taken along the line 3—3 in Fig. 4; Fig. 4 is a fragmentary plan view, partly in section, of the ion source unit; Fig. 5 is a fragmentary plan view of the inner end of the ion source unit, illustrating the position of the filamentary cathodes with respect to the associated arc-block; and Fig. 6 is a fragmentary front elevational view of the inner end of the source unit, taken along the line 6—6 in Fig. 4, further illustrating the relative position of the filamentary cathodes and the arc-block.

Referring now more particularly to Figs. 1 and 2 of the drawings, there is illustrated a calutron 10 incorporating an ion source unit 11 embodying the features of the present invention. More particularly, the calutron 10 comprises magnetic field structure including upper and lower pole pieces 12 and 13 provided with substantially flat parallel spaced-apart pole faces, and a tank 14 disposed between the pole faces of the pole pieces 12 and 13. The pole pieces 12 and 13 carry windings, not shown, that are adapted to be energized in order to produce a substantially homogeneous and relatively strong magnetic field therebetween, which magnetic field passes through the tank 14 and the various parts housed therein. The

tank 14 is of tubular configuration, being substantially crescent-shaped in plan and comprising substantially flat parallel spaced-apart top and bottom walls 15 and 16, upstanding curved inner and outer side walls 17 and 18, and end walls 19 and 20. The end walls 19 and 20 close the opposite ends of the tubular tank 14 and are adapted to be removably secured in place, whereby the tank 14 is hermetically sealed. Also, vacuum pumping apparatus 21 is associated with the tank 14, whereby the interior of the tank 14 may be evacuated to a pressure of the order of 10^{-5} to 10^{-4} mm. Hg. Preferably, the component parts of the tank 14 are formed of steel, the top and bottom walls 15 and 16 thereof being spaced a short distance from the pole faces of the upper and lower pole pieces 12 and 13 respectively, the tank 14 being retained in such position in any suitable manner, whereby the top and bottom walls 15 and 16 constitute in effect pole pieces with respect to the interior of the tank 14, as explained more fully hereinafter.

The source unit 11 is carried by the removable end wall 19; and the source unit 11 comprises a charge receptacle 22 disposed exteriorly of the tank 14 and a communicating arc-block 23 positioned within the tank 14. An electric heater 24 is arranged in heat exchange relation with the charge receptacle 22 and is adapted to be connected to a suitable source of heater supply, whereby the charge receptacle 22 may be appropriately heated. The arc-block 23 is of hollow construction and the cavity therein communicates with the interior of the charge receptacle 22. Also, two laterally spaced-apart upstanding slots 25 and 26 are formed in the wall of the arc-block 23, disposed remote from the charge receptacle 22.

Further, the removable end wall 19 carries two filamentary cathodes 27 and 28, adapted to be connected to a suitable source of filament supply, the filamentary cathodes 27 and 28 overhanging the upper end of the arc-block 23 and arranged in alignment with respect to the upper end of the cavity formed therein respectively adjacent the upstanding slots 25 and 26. More particularly, the source of filament supply is connected by way of a series resistor 29 across a potential divider 30 of the resistance type, provided with an adjustable wiper 31. The two filamentary cathodes 27 and 28 are connected in series circuit relation with respect to each other and to the potential divider 30, the outer terminals of the filamentary cathodes 27 and 28 being respectively connected to the outer terminals of the potential divider 30, and the inner terminals of the filamentary cathodes 27 and 28 being joined together and connected to the wiper 31. Accordingly, it will be understood that the potential applied across the potential divider 30 via the series resistor 29 from the source of filament supply may be appropriately divided across the filamentary cathodes 27 and 28 by adjustment of the wiper 31 of the potential divider 30.

The arc-block 23 carries an anode 32, disposed adjacent the lower end thereof and arranged in alignment with respect to the cavity formed therein. Also, the arc-block 23 carries a collimating electrode 33 disposed adjacent the upper end thereof, and having two elongated collimating slots 34 and 35 formed therethrough and respectively arranged in alignment with respect to the filamentary cathodes 27 and 28, as well as in common alignment with respect to the anode 32 and the cavity formed in the arc-block 23. Both the anode 32 and the collimating electrode 33 are electrically connected to the source unit 11, which in turn is grounded; likewise, the tank 14 is grounded. Also, the filamentary cathodes 27 and 28 and the cooperating anode 32 are adapted to be connected to a suitable source of arc supply.

Further, the removable end wall 19 carries ion accelerating structure 36, disposed in spaced-apart relation with respect to the wall of the arc-block 23 in which the slots 25 and 26 are formed. More specifically, two slits 37 and 38 are formed in the ion accelerating structure 36 and arranged in substantial alignment with respect to the two

slots 25 and 26 formed in the wall of the arc-block 23. A suitable source of accelerating electrode supply is adapted to be connected between the arc-block 23 and the ion accelerating structure 36, the positive and negative terminals of the supply mentioned being respectively connected to the arc-block 23 and to the ion accelerating structure 36. Further, the positive terminal of the accelerating electrodes supply is grounded.

The removable end wall 20 suitably supports two collector blocks 39 and 40 arranged in laterally spaced-apart relation, each formed of stainless steel or the like, and being provided with two laterally spaced-apart cavities or pockets which respectively communicate with two aligned slots formed in the wall of the collector block 15 disposed remote from the removable end wall 20. Specifically, the collector block 39 comprises the two laterally spaced-apart pockets 41 and 42, respectively communicating with the aligned slots 43 and 44 formed in the wall thereof disposed remote from the removable end wall 20; while the collector block 40 comprises the two laterally spaced-apart pockets 45 and 46, respectively communicating with the aligned slots 47 and 48 formed in the wall thereof disposed remote from the removable end wall 20. It is noted that the two pockets 41 and 25 42 formed in the collector block 39, as well as the two pockets 45 and 46 formed in the collector block 40, are adapted to receive two constituent isotopes of an element that have been separated in the calutron 10, as explained more fully hereinafter.

Further, the inner wall 17 suitably supports a tubular liner 49, formed of copper or the like, rectangular in vertical cross section, disposed within the tank 14 and spaced from the walls 15, 16, 17, and 18. One end 30 of the tubular liner 49 terminates adjacent the ion accelerating structure 36; and the other end of the tubular liner 49 terminates adjacent the collector blocks 39 and 40; the tubular liner 49 constituting an electrostatic shield for the high-velocity ions traversing curved paths between the slit 37 formed in the ion accelerating structure 36 and the slots 43 and 44 formed in the collector block 39, and the high-velocity ions traversing curved paths between the slit 38 formed in the ion accelerating structure 36 and the slots 47 and 48 formed in the collector block 40, as explained more fully hereinafter. Finally, the tubular liner 49 is electrically connected to the ion accelerating structure 36 and to the collector blocks 39 and 40, the collector block 39 being electrically connected to the collector block 40. Thus, it will be understood that the source unit 11 and the tank 14 are connected to the positive grounded terminal of the accelerating electrode supply; while the ion accelerating structure 36, the tubular liner 49, and the collector blocks 39 and 40 are connected to the negative ungrounded terminal of the accelerating electrode supply; the ion accelerating structure 36, the tubular liner 49, and the collector blocks 39 and 40 being electrically insulated from the component parts of the tank 14.

Considering now the general principle of operation of the calutron 10, a charge comprising a compound of the element to be treated is placed in the charge receptacle 22, the compound of the element mentioned being one that may be readily vaporized. The end walls 19 and 20 are securely attached to the open ends of the tank 14, whereby the tank 14 is hermetically sealed. The various electrical connections are completed and operation of the vacuum pumping apparatus 21 associated with the tank 14 is initiated. When a pressure of the order of 10^{-5} to 10^{-4} mm. Hg is established within the tank 14, the electric circuits for the windings, not shown, associated with the pole pieces 12 and 13 are closed and adjusted, whereby a predetermined magnetic field is established therebetween traversing the tank 14. The electric circuit for the heater 24 is closed, whereby the charge in the charge receptacle 22 is heated and vaporized. The vapor fills the charge receptacle 22 and is

conducted into the communicating cavity formed in the arc-block 23. The electric circuits for the filamentary cathodes 27 and 28 are closed and the wiper 31 is adjusted with respect to the potential divider 30, whereby the filamentary cathodes 27 and 28 are heated and rendered electron emissive. Then the electric circuit between the filamentary cathodes 27 and 28 and the anode 32 is closed, whereby arc discharges are struck therebetween, electrons proceeding from the filamentary cathode 27 through the collimating slot 34 formed in the collimating electrode 33 to the anode 32, and from the filamentary cathode 28 through the collimating slot 35 formed in the collimating electrode 33 to the anode 32. The collimating slot 34 formed in the collimating electrode 33 defines the cross section of the associated stream of electrons proceeding from the filamentary cathode 27 into the arc-block 23, whereby the accompanying arc discharge has a ribbon-like configuration; similarly, the collimating slot 35 formed in the collimating electrode 33 defines the cross section of the associated stream of electrons proceeding from the filamentary cathode 28 into the arc-block 23, whereby the accompanying arc discharge has a ribbon-like configuration. The arc discharges in the arc-block 23 break up the molecular form of the compound of the vapor to a considerable extent, producing positive ions of the element that is to be enriched with the selected one of its isotopes.

The electric circuit between the arc-block 23 and the ion accelerating structure 36 is completed, the ion accelerating structure 36 being at a high negative potential with respect to the arc-block 23, whereby the positive ions in the arc-block 23 are attracted by the ion accelerating structure 36 and accelerated through the voltage impressed therebetween. More particularly, the positive ions proceed from the cavity formed in the arc-block 23 through the slots 25 and 26 formed in the wall thereof, and across the space between the ion accelerating structure 36 and the adjacent wall of the arc-block 23, and thence through the respective slits 37 and 38 formed in the ion accelerating structure 36 into the interior of the tubular liner 49. The high-velocity positive ions form two vertical upstanding ribbons or beams proceeding from the cavity formed in the arc-block 23 through the slots 25 and 26 and the respectively aligned slits 37 and 38, into the tubular liner 49.

As previously noted, the collector blocks 39 and 40, as well as the tubular liner 49, are electrically connected to the ion accelerating structure 36, whereby there is an electric-field-free path for the high-velocity positive ions disposed between the ion accelerating structure 36 and the collector blocks 39 and 40 within the tubular liner 49. The high-velocity positive ions entering the adjacent end of the liner 49 are deflected from their normal straight-line paths and from vertical planes respectively passing through the slot 25 and the associated aligned slit 37, and through the slot 26 and the associated aligned slit 38, due to the effect of the relatively strong magnetic field maintained through the space within the tank 14 and the liner 49 through which the positive ions travel, whereby the positive ions describe arcs the radii of which are proportional to the square roots of the masses of the ions and consequently of the isotopes of the element mentioned. Thus, ions of the relatively light isotope of the element proceeding through the slit 37 describe an interior arc of relatively short radius and are focused through the slot 43 into the pocket 41 formed in the collector block 39; whereas ions of the relatively heavy isotope of the element proceeding through this slit describe an exterior arc of relatively long radius and are focused through the slot 44 into the pocket 42 formed in the collector block mentioned. Similarly, ions of the relatively light isotope of the element proceeding through the slit 38 describe an interior arc of relatively short radius and are focused through the slot 47 into the pocket 45 formed in the collector block 40; whereas ions of the relatively

heavy isotope of the element proceeding through this slit describe an exterior arc of relatively long radius and are focused through the slot 48 into the pocket 46 formed in the collector block mentioned. Accordingly, the ions of the relatively light isotope of the element are collected in the pockets 41 and 45 of the respective collector blocks 39 and 40 and are de-ionized to produce deposits of the relatively light isotope of the element therein; while the ions of the relatively heavy isotope of the element are collected in the pockets 42 and 46 of the respective collector blocks 39 and 40 and are de-ionized to produce deposits of the relatively heavy isotope of the element therein. Further, it will be observed that the beam of positive ions proceeding through the slit 37 formed in the ion accelerating structure 36 and directed to the collector block 39 intersects or crosses the beam of positive ions proceeding through the slit 38 formed in the ion accelerating structure 36 and directed to the collector block 40.

20 After all of the charge in the charge receptacle 22 has been vaporized, another charge may be placed therein without interrupting operation of the calutron 10, in a manner more fully explained hereinafter, and subsequently vaporized in the manner explained above. After a suitable number of such charges have been vaporized in order to obtain appropriate deposits of the isotopes of the element in the pockets 41, 42, and 45, 46 of the collector blocks 39 and 40, respectively, the end wall 20 may be removed and the deposits of the collected isotopes in the pockets in the collector blocks 39 and 40 may be reclaimed in any suitable manner.

Of course it will be understood that the various dimensions of the parts of the calutron 10, the various electrical potentials applied between the various electrical parts thereof, as well as the strength of the magnetic field between the pole pieces 12 and 13, are suitably correlated with respect to each other depending upon the mass numbers of the several isotopes of the element that is to be treated therein. In this connection, reference is again made to the previously-mentioned copending application of Ernest O. Lawrence for a complete specification of a calutron especially designed for the production of uranium enriched with the isotope U^{235} ; and further reference is made to the copending application of Ernest O. Lawrence, Serial No. 536,401, filed May 19, 1944, now U. S. Patent No. 2,714,664, disclosing a calutron of the multiple ion beam type of the general character described above. By way of illustration, it is noted that when the calutron 10 is employed in order to produce uranium enriched with U^{235} , the compound of uranium which is suggested as a suitable charge in the charge receptacle 22 is uranium hexachloride; a calutron utilizing UCl_6 is disclosed in the copending application of Francis A. Jenkins, Serial Number 563,952, filed November 17, 1944; and the compound of UCl_6 , as well as the process of making it, is disclosed in the copending application of Francis A. Jenkins, Serial No. 494,447, filed July 13, 1943, now U. S. Patent No. 2,572,156, granted October 23, 1951.

60 The compound UCl_6 is very advantageous, as it may be readily vaporized and the molecular form of the vapor may be readily broken up to form positive ions of uranium with great facility. In this case, uranium enriched with U^{235} is collected in the pockets 41 and 45 of the collector blocks 39 and 40, respectively, and uranium comprising principally U^{238} is collected in the pockets 42 and 46 of the collector blocks mentioned. Also, it is noted that from a practical standpoint the deposits of uranium collected in the pockets 41 and 45 of the collector blocks 39 and 40, respectively, contain considerable amounts of U^{238} , in view of the fact that this isotope comprises the dominant constituent of natural or normal uranium. Furthermore, the deposits of uranium collected in the pockets 41 and 45 of the collector blocks 39 and 40 contain a considerably increased amount of U^{234} , in view of

the fact that it is not ordinarily feasible to separate U²³⁴ and U²³⁵ in the production of relatively large quantities of uranium enriched with U²³⁵ for commercial purposes. Accordingly, in this example the uranium deposited in the pockets 41 and 45 of the collector blocks 39 and 40, respectively, is considerably enriched both with U²³⁴ and U²³⁵, and considerably impoverished with respect to U²³⁸ as compared to natural or normal uranium.

Referring now more particularly to Figs. 3 to 6, inclusive, of the drawings, there are illustrated the structural details of the source unit 11 which is carried by the removable end wall 19 of the tank 14 and comprises the charge receptacle 22 and the arc-block 23, as previously explained. More particularly, the source unit 11 comprises a substantially horizontally disposed elongated tubular member 50 extending through an opening formed in the removable end wall 19 of the tank 14, the charge receptacle 22 being carried by the outer end of the tubular member 50 and disposed exteriorly of the tank 14, and the arc-block 23 being carried by the inner end of the tubular member 50 and positioned within the tank 14. The member 50 includes a cylindrical inner tube 51 and a cylindrical outer tube 52, arranged in telescoped relation to define a space therebetween which receives an elongated helical electric heater 53 and a suitable embedding packing of heat and electrical insulating material 54. Preferably, the electric heater 53 closely surrounds the inner tube 51 in good heat-exchange relation therewith, and the insulating packing 54 embedding the electric heater 53 completely fills the space between the tubes 51 and 52. Thus, the tubular member 50 may be heated in order to prevent condensation of the vapor contained in the inner tube 51, as explained more fully hereinafter.

The arc-block 23 includes two primary members 55 and 56, formed of copper or brass and secured together in any suitable manner, the member 55 being directly secured and hermetically sealed to the inner end of the inner tube 51, the inner end of the tube 51 terminating in an opening formed in the member 55. Also, the member 55 is secured and hermetically sealed to the outer tube 52 by an arrangement including a ring 57 surrounding the outer tube 52. An upstanding cavity 58 is formed in the member 55 and communicates with the inner tube 51, the cavity 58 constituting a distributing chamber. Also, two upstanding cavities 59 are formed in the member 55 on opposite sides of the distributing chamber 58 and receive electric heating elements 60. Thus, the arc-block 23 and more particularly the distributing chamber 58 therein may be heated in order to prevent condensation of the contained vapor, as explained more fully hereinafter.

Two laterally spaced-apart upstanding arc chambers 61 and 62 are formed in the member 56, and two laterally spaced-apart series of longitudinally spaced-apart openings 63 and 64 are formed in the member 56 and respectively communicate with the arc chambers 61 and 62. More particularly, the openings 63 and 64 are arranged in pairs and are connected together by a plurality of laterally extending longitudinally spaced-apart manifold passages 65, formed in the member 56 and communicating with the distributing chamber 58. Thus, the extreme inner end of the inner tube 51 communicates with the distributing passage 58, which in turn communicates with the manifold passages 65 which are connected to the openings 63 and 64, the openings 63 and 64 respectively communicating with the arc chambers 61 and 62.

Three upstanding strips 66, 67, and 68, formed of tungsten or the like, are secured to the face of the member 56 in cooperating relation with the arc chambers 61 and 62. More particularly, the two strips 66 and 67 comprise a portion of the wall structure of the arc chamber 61 and are arranged in laterally spaced-apart relation to define an upstanding slot therebetween com-

municating with this arc chamber; and the two strips 67 and 68 comprise a portion of the wall structure of the arc chamber 62 and are arranged in laterally spaced-apart relation to define an upstanding slot therebetween communicating with this arc chamber. Also, three upstanding strips 69, 70, and 71, formed of tungsten or the like, are secured to the member 56, respectively adjacent the strips 66, 67, and 68 and spaced a small distance forwardly with respect thereto. More particularly, the strips 69 and 70 define an upstanding slot therebetween communicating with the arc chamber 61; and the strips 70 and 71 define an upstanding slot therebetween communicating with the arc chamber 62. Thus, the slot defined between the strips 66 and 67 and the slot defined between the strips 69 and 70 constitute the composite slot 25 formed in the front wall of the arc-block 23; and the slot defined between the strips 67 and 68 and the slot defined between the strips 70 and 71 constitute the composite slot 26 formed in the front wall of the arc-block 23. Specifically, the composite slots 25 and 26 formed in the front wall of the arc-block 23 and communicating with the cavity formed therein, as previously noted, actually communicate respectively with the arc chambers 61 and 62 formed in the member 56. Also, two upstanding semicircular baffle plates 61a and 62a, formed of quartz or the like, are respectively arranged in the arc chambers 61 and 62, each of the baffle plates mentioned having a series of longitudinally spaced-apart openings formed therein for a purpose more fully explained hereinafter.

Cathode structure 72 is supported over the arc-block 23 and carries the two filamentary cathodes 27 and 28 previously noted. The cathode structure 72 comprises a tubular shell 73 carried by the removable end wall 19 of the tank 14 upon an insulator, not shown, and houses three conductors 74, 75, and 76, suitably insulated from each other and respectively terminating in three terminals 77, 78, and 79 which support the filamentary cathodes 27 and 28. More particularly, each of the two filamentary cathodes 27 and 28 is substantially U-shaped and the legs thereof are removably clamped in place upon the terminals 77, 78, and 79 by an arrangement including three detachable clamping plates 80, 81, and 82. More specifically, the two legs of the filamentary cathode 27 are respectively clamped upon the two terminals 77 and 78 by the two clamping plates 80 and 81; while the two legs of the filamentary cathode 28 are respectively clamped upon the two terminals 78 and 79 by the two clamping plates 81 and 82. Accordingly, the two outer legs of the two filamentary cathodes 27 and 28 are respectively connected to the two conductors 74 and 76, and the two inner legs of the two filamentary cathodes 27 and 28 are commonly connected to the conductor 75 by the arrangement described.

The two filamentary cathodes 27 and 28 overhang the top wall of the arc-block 23 as previously noted, and the collimating electrode 33 is directly secured to the member 56, the collimating electrode 33 having the two laterally spaced-apart and transversely extending slots 34 and 35 formed therein and respectively communicating with the arc chambers 61 and 62. More particularly, the filamentary cathode 27 is spaced a short distance above the collimating electrode 33, the central portion of the filamentary cathode 27 being arranged in alignment with the corresponding transverse slot 34 formed in the collimating electrode 33 and communicating with the arc chamber 61; and the filamentary cathode 28 is spaced a short distance above the collimating electrode 33, the central portion of the filamentary cathode 28 being arranged in alignment with the corresponding transverse slot 35 formed in the collimating electrode 33 and communicating with the arc chamber 62.

The anode 32 is secured to the bottom wall of the arc-block 23, as previously noted, and directly to the lower

end of the member 56, closing the lower ends of the arc chambers 61 and 62. The anode 32 is in alignment with the central portions of the filamentary cathodes 27 and 28 and the two transverse slots 34 and 35 formed in the collimating electrode 33. The negative terminal of the arc supply is connected to the conductors 74, 75, and 76, and consequently to the filamentary cathodes 27 and 28; and the positive terminal of the arc supply is connected to the arc-block 23 and consequently to the anode 32 and the collimating electrode 33.

The ion accelerating structure 36 associated with the arc-block 23 comprises three upstanding laterally spaced-apart strips 83, 84, and 85, supported by two laterally extending members 86 and 87, the ion accelerating structure 36 being disposed forwardly of the arc-block 23 and being supported upon an insulator, not shown, carried by the removable end wall 19 of the tank 14, as previously noted. The two strips 83 and 84 carry two electrodes 88, formed of tungsten or the like, and arranged in laterally spaced-apart relation to define the upstanding slit 37 in the ion accelerating structure 36, the slit 37 being arranged in alignment with the slot 25 formed in the front wall of the arc-block 23 and communicating with the arc chamber 61, as previously noted. The two strips 84 and 85 carry two electrodes 89, formed of tungsten or the like, and arranged in laterally spaced-apart relation to define the upstanding slit 38 in the ion accelerating structure 36, the slit 38 being arranged in alignment with the slot 26 formed in the front wall of the arc-block 23 and communicating with the arc chamber 62, as previously noted. The positive and negative terminals of the accelerating electrode supply are respectively connected to the arc-block 23 and the ion accelerating structure 36, as previously noted.

The charge receptacle 22 comprises a charge bottle 90, formed of glass or the like and hermetically secured to an annular plate 91 which in turn is supported by an annular disk 92, directly secured to the outer surface of the removable end wall 19 of the tank 14. More particularly, the annular disk 92 surrounds the tubular member 50 and carries two supporting brackets 93 disposed on opposite sides of the outer end of the tubular member 50 and secured directly to the upper surface of the annular plate 91.

The lower end of an upstanding cylindrical shell 94 is secured to the central portion of the annular plate 91 and has an opening in the cylindrical side wall thereof into which the extreme outer end of the outer tube 52 of the tubular member 50 is secured. The upper end of the cylindrical shell 94 is secured to a ring 95, to which a removable annular cover plate 96 is secured. The portion of the outer tube 52 disposed between the shell 94 and the annular disk 92, as well as the portion of the shell 94 disposed between the annular plate 91 and the ring 95, is encased in a body of suitable thermal insulating material 97.

A centrally disposed opening 98, comprising a gas port, is formed in the annular plate 91; and the lower end of an upstanding cylindrical tube 99 is hermetically secured to the annular plate 91 about the port 98. The tube 99 is disposed within the shell 94 and has an opening in the cylindrical side wall thereof into which the extreme outer end of the inner tube 51 of the tubular member 50 is hermetically secured. The upper end of the upstanding tube 99 carries a substantially inverted cup-shaped member 100, also arranged within the shell 94. Further, the upper end of the upstanding tube 99 is hermetically sealed to a flexible bellows 101 arranged within the member 100.

An upstanding valve stem 102 is arranged for vertical movement within the upstanding tube 99 and is hermetically sealed to the flexible bellows 101, the lower end of the valve stem 102 projecting through the port 98 formed in the annular plate 91. More particularly, the intermediate portion of the valve stem 102 is supported for

sliding vertical movement by a spider 103 arranged within the upstanding tube 99, while the upper end of the valve stem 102 is supported for sliding vertical movement by the end wall of the member 100, the upper end of the valve stem 102 projecting through an opening formed in the end wall of the member 100. The valve stem 102 is provided with a threaded portion 104 adjacent the extreme upper end thereof, which is arranged in threaded engagement with a bevel gear 105, rotatably supported in an annular bearing 106 carried in an annular opening formed in the cover plate 96. The bevel gear 105 is retained in position by a hollow block 107 secured to the cover plate 96, and is arranged in meshing engagement with a cooperating bevel gear 108, which is supported on a rotatable spindle 109 journaled in an opening formed in a block 110 secured to the cover plate 96, the outer end of the spindle 109 carrying a handle 111 to facilitate rotation thereof.

Accordingly, it will be understood that the spindle 109 may be rotated in either direction by the handle 111, in order to effect corresponding rotation of the bevel gear 108 carried thereby and consequent rotation of the bevel gear 105 in either direction. When the bevel gear 105 is rotated in one direction, the threaded end 104 of the valve stem 102 is forced to travel upwardly, whereby the valve stem 102 moves upwardly in the upstanding tube 99 with respect to the port 98 formed in the annular plate 91; and when the bevel gear 105 is rotated in the other direction, the threaded end 104 of the valve stem 102 is forced to travel downwardly, whereby the valve stem 102 moves downwardly in the upstanding tube 99 with respect to the port 98 formed in the annular plate 91. It will be understood that the flexible bellows 101 accommodates movement of the valve stem 102 in either direction, retaining the hermetic seal established between the port 98 formed in the annular plate 91 and the upstanding tube 99 and the connected inner tube 51 of the tubular member 50. Further, it is pointed out that the outer tube 52 of the tubular member 50 is hermetically sealed to the removable end wall 19 of the tank 14, preferably by a welded joint, as indicated at 112. Thus, it will be understood that the substantially fluid-tight character of the tank 14 is not altered in any way by the fact that the interior of the shell 94 may not be hermetically sealed with respect to the exterior, in view of the fact that the removable end wall 19 of the tank 14 is hermetically sealed to the outer tube 52, which in turn is hermetically sealed to the ring 57; and the ring 57 is hermetically sealed to the member 55, which in turn is hermetically sealed to the inner tube 51.

The charge bottle 90 comprises a substantially spherical lower body portion 113 containing a charge 114 of UCl_6 , as previously noted, and a substantially cylindrical neck 115 providing an open throat into which the lower end of the valve stem 102 projects. More particularly, the neck 115 of the charge bottle 90 terminates in an annular flange 116 that is hermetically secured to the lower surface of the annular plate 91 by an arrangement including an annular clamping collar 117 of the split type. The annular clamping collar 117 surrounds the neck 115 of the charge bottle 90 and engages the annular flange 116 thereof, the clamping collar 117 being secured directly to the lower surface of the annular plate 91 by an arrangement including a series of screws 118. Preferably, a flexible annular gasket 119 is disposed between the annular flange 116 carried by the neck 115 of the charge bottle 90 and the clamping collar 117, and an annular gasket 120 is arranged in an annular groove formed in the lower surface of the annular plate 91 in engagement with the annular flange 116, in order positively to insure a hermetic seal between the charge bottle 90 and the annular plate 91.

As previously noted, the body portion 113 of the charge bottle 90 contains a charge 114 of UCl_6 which is originally sealed against the atmosphere by an arrangement

ment including a frangible wall 121 disposed in the neck 115 of the charge bottle 90, the frangible wall 121 being disposed below the open throat of the charge bottle 90. The lower end of the valve stem 102 projects through the port 98 formed in the annular plate 91 into the open throat of the charge bottle 90, and carries a valve element or plate 122 which is adapted to cooperate with an annular ring 123 disposed in an annular groove formed in the lower surface of the annular plate 91 in surrounding relation with respect to the port 98. Preferably, the annular ring 123 is formed of brass or the like and constitutes a seat for the valve port 98 formed in the annular plate 91. Also, the extreme lower end of the valve stem 102 carries a fixture 124 disposed immediately above the frangible wall 121, which fixture 124 is adapted to be moved into puncturing or striking engagement with the frangible wall 121.

In view of the above description, it will be understood that after a sealed charge bottle 90 has been hermetically secured to the annular plate 91, the charge 114 contained in the body portion 113 thereof may be opened into communication with the port 98 formed in the annular plate 91 in a ready manner, by operating the handle 111 in order to cause the valve stem 102 to be forced downwardly, causing the fixture 124 carried on the lower end of the valve stem 102 to engage the frangible wall 121, whereby the wall 121 is broken or punctured. Thereafter, the handle 111 may be operated in order to cause the valve stem 102 to be forced upwardly, whereby the valve element 122 is brought into cooperative relation with respect to the valve seat 123 in order to throttle the flow of vapor through the port 98 formed in the annular plate 91, the charge 114 contained in the body portion 113 of the charge bottle 90 having been converted to vapor by heating, as explained more fully hereinafter.

Further, the charge receptacle 22 comprises a substantially cup-shaped casing 125 carrying an annular ring 126 adjacent the upper edge thereof, the ring 126 being secured to the annular plate 91 adjacent the periphery thereof by a plurality of screws 127. The outer surface of the casing 125 supports a body of suitable thermal insulating material 128; and a substantially cup-shaped receptacle 129 is arranged within the casing 125 in surrounding and spaced-apart relationship with respect to the charge bottle 90. A sealing gasket 130 is arranged mutually between the lower surface of the annular plate 91, the ring 126, and the upper edge of the receptacle 129, thereby to provide a substantially fluid-tight seal therebetween. The electric heater 24 is embedded in the wall of the receptacle 129, and a body 132 of a suitable light oil fraction, such as a paraffinic petroleum oil fraction having a relatively narrow boiling range, is contained within the receptacle 129, submerging the body portion 113 of the charge bottle 90. Further, a thermocouple 133 is carried by the annular plate 91 and extends into the body of oil 132 so that the temperature thereof may be measured or recorded. Finally, an upstanding helical electric heater 134 is arranged within the shell 94 in surrounding relationship with respect to the upstanding tube 99 and the member 100, in order to prevent condensation of vapor therein.

Considering now the detailed operation of the ion source unit 11 and assuming that the casing 125 and the receptacle 129 carried thereby, as well as the charge bottle 90, have been removed from the plate 91, and that the handle 111 has been operated in order to move the valve stem 102 upwardly, causing the valve element 122 to engage the seat 123, the port 98 formed in the plate 91 is closed against the admission of air into the upstanding tube 99 and consequently into the tank 14, whereby the tank 14 is rendered substantially fluid-tight. At this time, the clamping collar 117 is placed about the neck 115 of a charge bottle 90 which has been previously prepared and sealed, the body portion 113 of the charge bottle 90 containing a charge 114 of UCl_6 and the frangi-

ble wall 121 being intact. The charge bottle 90 and the clamping collar 117 are then brought in place with respect to the annular plate 91 and the screws 118 are set in order securely to clamp the annular flange 116 disposed about the neck 115 of the charge bottle 90 against the lower surface of the annular plate 91, and to effect a hermetic seal therebetween. At this time, the casing 125 supporting the receptacle 129 containing the body of light oil 132 is brought into position and secured to the annular plate 91 by setting the screws 127.

The handle 111 is then manipulated in order to force the valve stem 102 downwardly, causing the fixture 124 carried on the extreme lower end thereof to strike the frangible wall 121, whereby this wall is broken or punctured, opening the body portion 113 of the charge receptacle 90 and the contained charge of UCl_6 114 into communication with the interior of the upstanding tube 99 and the communicating inner tube 51. The circuits for the electric heaters 24, 134, and 53 are closed; the electric heater 24 effecting heating of the receptacle 129 and the contained body of oil 132, the electric heater 134 effecting heating of the upstanding tube 99 and the member 100, and the electric heater 53 effecting heating of the inner tube 51.

More particularly, the body of oil 132 is heated to a temperature within the range 80° to 180° C. as indicated by the arrangement including the thermocouple 133, whereby the body portion 113 of the charge receptacle 90 is heated in order to effect heating of the charge of UCl_6 114. At this time, the interior of the tank 14 is evacuated to a pressure of the order of 10^{-5} to 10^{-4} mm. Hg, whereby a low pressure somewhat higher than that mentioned above is maintained in the cavities in the arc-block 23 and consequently in the connecting inner tube 51, the upstanding tube 99, and the interior of the charge bottle 90. Under the conditions mentioned, the charge of UCl_6 114 is vaporized, filling the neck 115 of the charge bottle 90 and passing through the port 98 formed in the annular plate 91 into the upstanding tube 99 and communicating inner tube 51.

The quantity of vapor supplied from the charge bottle 90 through the port 98 formed in the annular plate 91 into the upstanding tube 99 and communicating inner tube 51 may be regulated, both by controlling the temperature of the body of oil 132 and consequently the heating of the charge of UCl_6 114 and by the valve mechanism including the valve element 122 and the valve seat 123 associated with the port 98 formed in the annular plate 91. More particularly, at this time the handle 111 may be manipulated in order to force the valve stem 102 upwardly, thereby bringing the valve element 122 into cooperative relation with respect to the valve seat 123, whereby the flow of vapor from the charge receptacle 90 into the upstanding tube 99 through the port 98 formed in the annular plate 91 is throttled in an obvious manner.

The UCl_6 vapor supplied from the charge bottle 90 into the inner tube 51 of the tubular member 50 flows into the distributing chamber 58 provided in the member 55 forming a part of the arc-block 23. The UCl_6 vapor fills the distributing chamber 58 and is distributed thereby into the manifold passages 65, from which it flows through the openings 63 and 64 formed in the member 56 into the rear parts of the arc chambers 61 and 62.

The vapor then passes through the openings formed in the baffle plates 61a and 62a into the front parts of the arc chambers 61 and 62, whereby these parts of the arc chambers mentioned are filled with the vapor. More particularly, each of the arc chambers 61 and 62 is thoroughly and substantially uniformly filled with the vapor to be ionized, due to the arrangement of the distributing chamber 58, the manifold passages 65, the communicating openings 63 and 64, and the associated baffle plates 61a and 62a.

When the filament supply circuit is completed, the filamentary cathodes 27 and 28 are heated and rendered

electron emissive; and when the arc supply circuit is completed between the filamentary cathodes 27 and 28 and the arc-block 23, electrons are projected from the central portion of each of the filamentary cathodes toward the collimating electrode 33. More particularly, some of the electrons from the central portion of each of the filamentary cathodes 27 and 28 pass through the respectively associated transverse slots 34 and 35 formed in the collimating electrode 33, into the respectively associated arc chambers 61 and 62, and proceed toward the anode 32. Accordingly, the collimating electrode 33 causes a stream of electrons having a ribbon-like configuration to be projected through each of the arc chambers 61 and 62, whereby the vapor in each of the arc chambers mentioned is ionized.

When the accelerating electrode supply circuit is completed between the arc-block 23 and the ion accelerating structure 36, the positive ions produced in the arc chambers 61 are drawn through the upstanding slot 25 formed in the front wall of the arc-block 23 to form the beam of positive ions having the upstanding substantially ribbon-like configuration, proceeding through the slit 37 between the electrodes 88 carried by the ion accelerating structure 36; which beam of positive ions is projected through the evacuated tank space toward the cooperating collector block 39 in the manner previously explained. Also, when the accelerating electrode supply circuit is completed between the arc-block 23 and the ion accelerating structure 36, the positive ions produced in the arc chamber 62 are drawn through the upstanding slot 26 formed in the front wall of the arc-block 23 to form the beam of positive ions having the upstanding substantially ribbon-like configuration proceeding through the slit 38 between the electrodes 89 carried by the ion accelerating structure 36; which beam of positive ions is projected through the evacuated tank space toward the cooperating collector block 40. in the manner previously explained.

Accordingly, it will be understood that the source unit 11 comprises two gas ionizing devices which are supplied from a single source of gas, and that this source unit 11 in conjunction with the associated ion accelerating structure 36 comprises two ion transmitters, arranged to transmit two beams of ions through the evacuated tank space in the tank 14 of the calutron 10 to the associated ion collecting apparatus in the form of the two collector blocks or receivers 39 and 40, in the manner previously explained.

Operation of the calutron 10 proceeds in the manner explained above until substantially all of the charge of UCl_6 114 contained in the charge bottle 90 is evaporated, at which time it is necessary to replace the substantially empty charge bottle 90 with another. This may be accomplished in a ready manner by manipulating the handle 111 in order to force the valve stem 102 upwardly, whereby the valve element 122 is brought into engagement with the valve seat 123, closing the port 98 formed in the annular plate 91. The screws 127 are removed, permitting removal from the annular plate 91 of the casing 125 carrying the receptacle 129 containing the body of oil 132. The screws 118 are then removed from the annular plate 91, thereby permitting removal of the clamping collar 117 and the spent charge bottle 90.

At this time, another charge bottle 90 containing a fresh charge of UCl_6 114 may be replaced, as well as the casing 125 carrying the receptacle 129 containing the body of oil 132, in cooperating relation with respect to the annular plate 91, all in the manner previously explained. At this time, the handle 111 may be again manipulated in order to break the frangible wall 121 carried by the new charge bottle 90, in order to open the charge bottle mentioned into communication with the port 98 formed in the annular plate 91, and thereafter the handle 111 may be manipulated in order to throttle the flow of vapor through the port 98 formed in the an-

nular plate 91 after the circuit for the electric heater 24 is again completed, all in the manner previously explained.

In view of the above description of the mode of operation of the source unit 11, it will be understood that 5 charge bottles may be replaced in a ready manner without appreciably increasing the pressure within the tank of the calutron and without serious interference with continuous operation of the calutron. Also, it will be appreciated that the mechanism carried by the source unit for breaking a new charge bottle into communication with the arc-block is also utilized for the purpose of regulating the flow of vapor therebetween.

While there has been described what is at present considered to be the preferred embodiment of the invention, 15 it will be understood that various modifications may be made therein and it is intended to cover in the appended claims all such modifications as fall within the true spirit and scope of the invention.

What is claimed is:

20 1. In a calutron including a substantially fluid-tight tank provided with evacuating means and a removable wall, an ion source unit comprising a tubular member carried by said wall, said tubular member extending through an opening formed in said wall and being hermetically sealed thereto, a gas ionizing device carried by the inner end of said tubular member and positioned within said tank, structure carried by the outer end of said tubular member and defining a gas reservoir disposed exteriorly of said tank and containing a charge 25 capable of being vaporized, means including a first heating element carried by and in thermal contact with said structure for vaporizing the charge contained in said gas reservoir, said tubular member communicating with said gas reservoir and said gas ionizing device, whereby the 30 gas produced in said gas reservoir as a result of the vaporization of the charge contained therein may be conducted through said tubular member and supplied to said gas ionizing device, and means including a second heating element carried by and in thermal contact with said 35 tubular member between said gas reservoir and said gas ionizing device for preventing the gas conducted therethrough from condensing therein.

40 2. An ion source unit capable of being evacuated comprising a member having a normally opened port therethrough, a normally closed receptacle containing a charge 45 and secured to said member in surrounding relation with respect to said port, and mechanism carried by said member for opening said receptacle and then for closing at least partially said port, whereby the charge in said receptacle is placed into communication with said port so that it is conducted therethrough and then the opening of said port is controlled in order to regulate the flow of the charge therethrough.

50 3. An ion source unit capable of being evacuated comprising a member having a normally opened port therethrough, a normally closed receptacle containing a charge 55 capable of being vaporized and secured to said member in surrounding relation with respect to said port, means including a heating element carried by said member and surrounding said receptacle for vaporizing the charge contained therein, and mechanism carried by said member for opening said receptacle and then for closing at least partially said port, whereby the charge in said receptacle is placed into communication with said port so that it is conducted therethrough and then the opening of said port is controlled in order to regulate the flow of the charge therethrough.

60 4. An ion source unit capable of being evacuated comprising a member having a port therethrough and provided with a surrounding valve seat, a valve stem extending through said port and carrying a valve element 65 adjacent one end thereof and in proximity to said valve seat, a receptacle provided with an open throat and secured to said member about said port, whereby the one 70

75 cured to said member about said port, whereby the one

end of said valve stem and said valve element are disposed in the open throat of said receptacle, said receptacle containing a charge capable of being vaporized and being normally sealed by an arrangement including a puncturable wall disposed adjacent the throat thereof and in proximity to the one end of said valve stem, means for vaporizing the charge contained in said receptacle, and means for imparting movement to said valve stem with respect to said member, whereby the one end of said valve stem may be moved into puncturing engagement with the puncturable wall of said receptacle and subsequently moved to bring said valve element into operating relation with respect to said valve seat.

5. An ion source unit capable of being evacuated comprising a member having a port therethrough and provided with a surrounding valve seat, a valve stem extending through said port and carrying a valve element adjacent one end thereof and in proximity to said valve seat, a receptacle provided with an open throat and secured to said member about said port, whereby the one end of said valve stem and said valve element are disposed in the open throat of said receptacle, said receptacle containing a charge capable of being vaporized and being normally sealed by an arrangement including a frangible wall disposed adjacent the throat thereof and in proximity to the one end of said valve stem, means for vaporizing the charge contained in said receptacle, and means for imparting movement to said valve stem with respect to said member, whereby the one end of said valve stem may be moved into breaking engagement with the frangible wall of said receptacle and subsequently moved to bring said valve element into operating relation with respect to said valve seat.

6. An ion source unit capable of being evacuated comprising a member having a port therethrough, a charge receptacle containing a charge capable of being vaporized and secured to said member in surrounding relation with respect to said port, another receptacle carried by said member and surrounding said charge receptacle and containing a quantity of liquid immersing said charge receptacle, means for heating the liquid contained in said other receptacle, thereby to vaporize the charge contained in said charge receptacle causing the vapor to flow through said port, and means including a valve element operatively associated with said port for controlling the flow of vapor therethrough.

7. An ion source unit capable of being evacuated comprising a member having a port therethrough, a receptacle containing a charge capable of being vaporized and secured to said member in surrounding relation with re-

spect to said port, another receptacle carried by said member and surrounding said charge receptacle and containing a quantity of liquid immersing said charge receptacle, means including a heating element embedded in the wall of said other receptacle for heating the liquid contained therein, thereby to vaporize the charge contained in said charge receptacle causing the vapor to flow through said port, and means including a valve element operatively associated with said port for controlling the flow of vapor therethrough.

10. An ion source unit capable of being evacuated comprising a member having a port therethrough and provided with a surrounding valve seat, hollow structure including a flexible bellows hermetically sealed to said member and communicating with said port, a valve element carried by said flexible bellows in proximity to said valve seat, a receptacle containing a gaseous charge and hermetically sealed to said member in communication with said port, and means for imparting motion to said flexible bellows, thereby to control the position of said valve element with respect to said valve seat, whereby the flow of gaseous charge from said receptacle through said port into said hollow structure may be selectively controlled.

15. In a calutron including a substantially fluid-tight tank provided with evacuating means and a removable wall, an ion source unit comprising a tubular member carried by said wall, said tubular member extending through an opening formed in said wall and being hermetically sealed thereto, a gas ionizing device carried by the inner end of said tubular member and positioned within said tank, removable structure defining a normally sealed charge receptacle without said tank, heater means carried by and in thermal contact with said receptacle for vaporizing said charge, valve mechanism interconnecting said charge receptacle and the outer end of said tubular member including means for breaking the seal of said charge receptacle and subsequently controlling the flow of vapor, and second heater means carried by and in thermal contact with said tubular member for preventing said vapor from condensing therein.
